UNITED STATES PATENT OFFICE.

ARTHUR MAX SCHUTZMAN, OF BATON ROUGE, LOUISIANA.

DENTAL CASTING DEVICE.

Application filed September 13, 1926. Serial No. 134,969.

This invention relates to devices for facilitating dental casting purposes particularly making molds of plaster of Paris and like substances as used in dentistry and for other similar purposes.

One object of the invention is to provide a cup-like container suited to receive a plastic material, means being associated whereby the plastic material used may be easily ejected from the cup-like container.

It is a further feature to provide an efficient rigid handle on the container, the same partially enveloping an inner tubular guide set in the ejector and provided with means to normally retain the ejector in relative adjustment thereon.

Another aim is to provide a removable cap on the guide, limiting the amount of movement relative to the handle, preventing the ejector plate from moving outwardly beyond the confines of the container and further providing a tightly closed chamber adapted to receive and retain small objects, as the nuggets of the material to be cast in the molds.

These several advantages, together with other, such as convenience in manipulation, neatness of appearance and cheapness of construction, are accomplished by the novel construction and arrangement of parts hereinafter described and shown in the accompanying drawing, forming a material part of this disclosure, and in which:—

Figure 1 is a perspective view of an embodiment of the invention as ready for operation.

Figure 2 is a longitudinal sectional view taken on line 2—2 of Figure 1.

Figure 3 is a bottom plan view of the device.

Figure 4 is a fragmentary perspective view of the outer part of the container handle, showing the spring detent.

Figure 5 is a similar perspective view of the inner end of the ejector guide prior to attachment to the plate.

Beginning with the container, designated by the numeral 10, it will be seen to consist of a cylinder open at one end and having a closed opposite end 11 disposed at a right angle.

The diameter and length of the container may be made as required and the joint uniting the closed end 11 to the handle 12 may be of any preferred type whereby a rigid inseparable connection is made; as shown

the end 11 has a central opening, the edge 13 of which is turned outwardly providing an annular space in which is received the corresponding edge 14 of a bead 15 on one end of a cylindrical tube constituting the handle 12.

Near the opposite end of the tube is an outstanding band 16 the portion of the tube extending therebeyond being slit to produce spring frictional detents 17 sprung inwardly to bear against the surface of the tubular guide 18, freely slidable within the handle 12.

Formed on the inner end of the member 18 are a plurality of prongs 19 arranged at uniformly spaced distances and adapted to enter corresponding openings arranged concentrically within a circular plate 20 fitted to neatly slide in the container 10 and constituting an ejector as will later be seen. The prongs 19 may be upset or otherwise secured within the openings or other methods of fastening be used, such for instance as spot welding.

The opposite end of the guide 18 is exteriorly screw threaded to fit within a knurled cap 21, the lower edge of which makes contact with the outer end of the handle 12 limiting the movement of the ejector disc 20 to a point substantially level with the lower edge of the container 10.

The cap 21 also acts as a closure for the tubular guide element 18 which thus presents a closed chamber 22 to receive small articles, as fragments or nuggets of gold to be used in casting objects in the mold made in the container 10, the making of such molds being familiar to those versed in the art.

From the foregoing it will be seen that a neat and very convenient device has been disclosed in the preferred form of its embodiment but it is to be understood that the description and drawings are to be taken as illustrative rather than restrictive, as obviously minor modifications may be made without departing from the scope and spirit of the invention as claimed.

Having thus described my invention, what I claim as new and desire to secure by Letters Patent, is:—

1. A dental casting device comprising a container having a rigid tubular handle to receive objects, an ejector movable in said container, a guide for said ejector slidable in said handle, a stop cap on said guide to contact with said handle when the ejector is in

an outermost position, and friction detents formed from said handle to engage said guide.

2. A dental casting device comprising a cylinder closed at one end and open at the other, a tubular handle extending axially from the closed end, a plunger snugly slideable in said cylinder, a hollow guide fixed on said plunger to extend outward beyond said handle, a screw cap removably engaged on said guide to form a chamber adapted to receive articles therein, said cap limiting the outward movement of said plunger, and a plurality of spring fingers formed at the outer end of said handle to frictionally impinge on said guide.

3. A dental casting device comprising a cylinder closed at one end and open at the other, said closed end having a central open-

ing provided with an out-turned annular flange spaced above the end wall, a tubular handle having a bead enveloping said flange, a plunger disc slidably fitting said container, a hollow guide having prongs rigidly fixed on said plunger said guide extending through and beyond said handle, a screw cap engaged on said guide to seat on the end of said handle when said disc is in its outermost position, said cap forming a closure to the chamber in said guide, a raised band on said handle, and a plurality of split spring fingers extending from said band to frictionally engage the surface of said guide to retain the same in an adjusted position.

Signed at Baton Rouge, in the parish of East Baton Rouge and State of Louisiana this 7th day of August A. D. 1926.

ARTHUR MAX SCHUTZMAN.
